No. 724,098.

PATENTED MAR. 31, 1903.

J. HEINEKE.

STRAW STACKER FOR THRESHING MACHINES.

APPLICATION FILED OCT. 15, 1902.

NO MODEL.

UNITED STATES PATENT OFFICE.

JOHN HEINEKE, OF SPRINGFIELD, ILLINOIS, ASSIGNOR OF TWO-THIRDS TO
MARTIN HEINEKE AND CHARLES HEINEKE, OF SPRINGFIELD, ILLINOIS.

STRAW-STACKER FOR THRESHING-MACHINES.

SPECIFICATION forming part of Letters Patent No. 724,098, dated March 31, 1903.

Application filed October 15, 1902. Serial No. 127,377. (No model.)

To all whom it may concern:

Be it known that I, JOHN HEINEKE, a citizen of the United States, residing at Springfield, in the county of Sangamon and State of Illinois, have invented certain new and useful Improvements in Straw - Stackers for Threshing-Machines, of which the following is a full, clear, and exact description, reference being had to the accompanying drawings, forming part of this specification.

My invention relates to a straw-stacker in which I utilize a pneumatic or blower carrier or ejector in connection with an endless carrier, whereby the straw is taken from the separator by the blower and delivered to the endless carrier.

The object of the invention is to furnish a construction that will embody the well-known merits of the blower to receive the straw from the separator and one that will provide for conveyance of the straw to the stack in a slow even stream without the objectionable blast delivery onto the stack from a pneumatic blower, to which is incident a constant cloud of dust and chaff that by its presence renders the labor of the workmen on the stack extremely difficult.

My present improvement has reference to a construction similar to that set forth in application for Letters Patent of the United States filed March 15, 1902, Serial No. 98,391.

The invention consists in features of novelty hereinafter fully described, and pointed out in the claims.

Figure I is a side elevation of my stacker. Fig. II is a longitudinal section taken through the stacker. Fig. III is a top or plan view of mechanism for hoisting the stacker-chute. Fig. IV is a view of a fragment of the hood or top of the stacker-chute.

1 designates a blower-tube that leads from a blower of any ordinary construction that is mounted in the separator or threshing-machine to which the stacker is applied.

2 is a rotatable tube surrounding the blower-tube 1 and revolvably mounted on a support 3, projecting from the rear end of the threshing-machine.

4 is a chute that is mounted upon a pivot 5, seated in horizontal bars 6, that are fixed to the rotatable tube 2 and extending for-

wardly therefrom. The pivot 5 swingingly supports the chute 4, so that it may be moved vertically to any desired inclination for the delivery of straw therethrough to the stack. 55

7 designates lever-arms fixed to the side of the chute 4, and 8 are windlass-cords connected to the arms 7. The cords 8 pass from the arms 7 to and beneath sheaves 9 and therefrom to drums 10, on which they are 60 adapted to be wound for the purpose of raising and lowering the chute 4. The sheaves 9 and drums 10 are mounted on shafts 11 and 12, which are seated in the horizontal bars 6.

13 is a ratchet-wheel on the shaft 12, and 14 is a pawl that engages with said ratchet-wheel and prevents retrograde rotation of said shaft and the drums thereon.

15 is an endless carrier arranged on rollers 16 and 17, mounted in the chute 4 at its ends 70 and adapted to travel through said chute. The shaft of the roller 16 has mounted upon it a pulley 18, that receives a belt 19, which is also applied to a pulley 20 on a driven shaft 21. On the shaft 21 is also a pulley 22, that 75 receives a driving-belt 23, through which power is communicated from the mechanism of the threshing-machine to the belt 19 to drive the endless carrier 15.

24 designates the hood or top of the chute 80 4. This hood is formed with a closed forward end and beyond the closed portion is provided with a plurality of perforations 25 (see Figs. II and IV) through which the air delivered into the chute 4 through the blower-tube and rotatable tube 1 is permitted to escape instead of acting as a blast upon the straw after it enters the chute and thereby tending to blow the straw through the chute. As a consequence of the exit of the air 85 through the perforated hood the straw delivered from the blower-tube is forced therefrom with only sufficient blast to cause it to fall onto the endless carrier 15.

In the practical use of my stacker the endless carrier 15 is driven in the manner stated, and as the straw is forced into the chute 4 under blast from the blower-tube it falls onto the endless carrier at the forward end of the chute and is gradually carried through the chute and discharged in an even and slow stream onto the stack, so that the workmen

whose duty it is to take the straw as it emerges from the chute and distribute it over the stack may stand close to the exit end of the chute without being discommodeed in the least by the annoying feature of the blast and consequent dust incident to the forcible ejection of the straw that is present in all purely pneumatic or blast stackers.

I claim as my invention—

- 10 1. In a straw-stacker, the combination with a blower-tube receiving straw directly from a threshing-machine separator, of a chute having a bottom, side walls and a top and having communication with said blower-tube, and an endless traveling carrier operating in said chute to convey the straw through said chute on its delivery from said blower-tube, substantially as set forth.
- 15 2. In a straw-stacker, the combination with

a blower-tube receiving straw directly from a threshing-machine separator, of a chute having communication with said blower-tube, an endless traveling carrier operating in said chute, said chute being provided with a perforated top or hood, substantially as described. 25

3. In a straw-stacker, the combination with a blower-tube receiving straw directly from a threshing-machine separator, of a chute having a closed bottom and side walls, an endless traveling carrier arranged in said chute, a hood forming the top of said chute, said hood being imperforate at its forward end and being provided with perforations at its rear end, substantially as set forth.

JOHN HEINEKE.

In presence of—

JOHN F. ARMSTRONG,
M. N. D'VIERA.
